UNITED STATES PATENT OFFICE.

WILLIAM HARVEY LOFTIN, OF JACKSONVILLE, FLORIDA, ASSIGNOR OF ONE-HALF TO
WILLIAM H. TAYLOR, OF JACKSONVILLE, FLORIDA.

ADJUSTABLE CRUTCH.

973,283.

Specification of Letters Patent. Patented Oct. 18, 1910.

Application filed February 7, 1910. Serial No. 542,553.

To all whom it may concern:

Be it known that I, WILLIAM HARVEY LOFTIN, a citizen of the United States, residing at Jacksonville, in the county of Duval and State of Florida, have invented a new and useful Adjustable Crutch, of which the following is a specification.

It is the object of this invention to provide a crutch adapted to be elongated or shortened, at will, to accommodate cripples of different statures.

Another object of the invention is to provide an adjustable hand hold for a crutch, arranged to be shifted to accommodate persons of different arm lengths.

Another object of the invention is to provide, in a crutch having telescopic parts, a means whereby said parts may be held in fixed positions with respect to each other.

Another object of the invention is to provide a crutch having telescopic parts, with a device which shall be effective, at once, as a means for maintaining said parts in fixed relation with respect to each other, and as a means for retaining a spring whereby the component parts of the crutch are held in proper position.

With the above and other objects in view, the invention consists in the novel construction and arrangement of parts hereinafter described, delineated in the accompanying drawings, and specifically claimed, it being understood that changes, properly falling within the scope of what is claimed, may be made, without departing from the spirit of the invention.

Similar numerals of reference are employed to denote corresponding parts throughout the several figures of the drawings.

In the accompanying drawings, Figure 1 is a perspective view of the crutch forming the subject matter of this application; Fig. 2 is a fragmental longitudinal section of the crutch; Fig. 3 is a fragmental plan thereof; Fig. 4 is a fragmental section of the hand-hold and the portion of the crutch which is connected therewith; Fig. 5 is a fragmental longitudinal section, showing a modified means for maintaining the hand hold in place; Fig. 6 is a transverse section of a portion of the device shown in Fig. 5; and Fig. 7 is a transverse section upon the line A—B of Fig. 2.

The crutch forming the subject matter of

this application consists of the usual spaced, convexed parts 1, united at their upper ends, by the shoulder piece 2. The intermediate portions of the parts 1 are spaced apart by means of the hand-hold 3, tubular in form, and having blocks 4 mounted in its ends. In the intermediate portions of the parts 1, there are a plurality of oppositely disposed openings 5. These openings 5 are adapted to receive the shank 6 of a screw, the screw, as shown most clearly in Fig. 4, entering the block 4 which is located within the tubular hand-hold 3. The head 7 of the screw bears against the outer face of the part 1, and is milled about its edge, or otherwise adapted to be seized for rotation. By removing the screws from one set of the openings 5, and inserting them in another set of said openings, the hand-hold 3 may be shifted longitudinally of the crutch to accommodate persons having different arm lengths. The lower ends of the parts 1 are brought together, and united by means of a rivet 8 or other retaining device adapted to a like end. The ends of the parts 1 which are thus brought together, are inserted into a tubular socket 9.

The crutch includes telescopic parts, tubular in form, the outer of which parts is denoted by the numeral 10. This part 10 is carried upwardly within the socket 9 to inclose the lower portion of the parts 1, as shown most clearly in Fig. 2. A pin 11 is passed through the socket 9, through the outer tube 10, and through those portions of the parts 1 which are disposed within the members 9 and 10.

Below the tubular socket 9, there is a longitudinally disposed opening 12 in the outer tube 10. As shown to best advantage in Fig. 3, this opening 12 comprises a straight portion 14, from which project alternating branches 15. An inner tube 16 is mounted for reciprocation within the outer tube 10. This inner tube 16 has at its lower end, secured thereto by threading or otherwise, a foot 17, provided with the usual resilient tip 18.

Mounted in the inner tube 16, adjacent its upper end, is a block 19, having in its upper face, an opening 20, adapted to receive the straight, lower end of a spring 22, the upper end 23 of which is secured about the pin 11.

The device is provided with an adjustable finger, shown in the present instance, in the form of a screw 24, inserted radially into

the inner tube 16, and into the block 19, the screw being of sufficient length to enter the opening 20 in which the end 21 of the spring 22 is mounted. This screw 24, protruding 5 from the inner tube 16, is adapted to traverse the portion 14 of the opening 12, and by rotating the tubular parts 10 and 16 upon each other, the screw may be made to enter one of the lateral branches 15 of the opening 12. The crutch may thus be lengthened 10 or shortened at will, the spring 22 serving to hold the screw 24 securely in one of the branches 15, preventing the telescoped parts from becoming separated, or rattling when 15 the device is in use.

In Figs. 5 and 6 of the drawings, a modified means for maintaining the hand hold 3 in position is shown.

If desired, the portions 1 of the crutch 20 may be provided with elongated openings 25. Located upon the adjacent faces of the parts 1, adjacent these openings 25 are plates 26 provided with serrations 27. There is a slot 28 in this plate 26, adapted 25 to be alined with the slot 25 in the part 1. Secured to the blocks 4 which are mounted in the ends of the hand-hold 3 are serrated plates 29. These plates 29 may be made to engage the plates 26 at points between their 30 ends, thus shifting the hand-holds longitudinally of the crutch, the screw 30 mov-

ing in the slots, and obviously constituting a means for holding the plates 29 in engagement with the plates 26.

Having thus described the invention, what is claimed is:—

1. In a crutch, the combination of telescopic parts; a spring connected at one end with one of said parts; and an adjustable finger mounted in the other part to engage 40 the first named part at predetermined steps, the finger constituting a means for connecting the other end of the spring with said other part.

2. In a crutch, the combination of telescopic parts; a spring connected at one end with the outer of said parts; the inner of said parts having a terminal opening to receive the other end of the spring; a screw 45 radially inserted into the inner part and arranged to engage the outer part at predetermined steps, the screw being movable into the opening to bind upon the last named end of the spring.

In testimony that I claim the foregoing 55 as my own, I have hereto affixed my signature in the presence of two witnesses.

WILLIAM HARVEY LOFTIN.
